MEAT MOLD

Don L. Tichenor, Battle Creek, Mich., assignor to
 United Steel & Wire Company, Battle Creek,
 Mich.

Application September 14, 1942, Serial No. 458,291

6 Claims. (Cl. 292—218)

The main objects of this invention are:

First, to provide a meat mold having highly effective means for securing the mold in closed position, at the same time permitting easy manipulation in closing the mold and in opening the same.

Second, to provide a structure having these advantages, which is very simple and economical to produce.

Further objects relating to details and economies of my invention will appear from the description to follow. The invention is defined in the claims.

A structure embodying the features of my invention is illustrated in the accompanying drawing, wherein:

Fig. 1 is a top view of a meat mold embodying the features of my invention, viewed from the standpoint of opening and closing.

Fig. 2 is an end view.

Fig. 3 is an enlarged fragmentary view in section on line 3—3 of Fig. 1.

Fig. 4 is a fragmentary perspective view further showing the relation of the latch and co-acting keeper members.

The mold illustrated in the accompanying drawing is of generally rectangular section and comprises two complementary wall members designated generally by numerals 1 and 2 (see Fig. 2) and each comprising longitudinal bars 3 formed of wire stock and angled cross pieces also formed of wire stock. The angled cross pieces 4 of the wall 1 terminate at one end in eyes 5 pivotally embracing longitudinal wall member 2. The angled cross members 6 of the wall member 2 are formed in pairs of single pieces of stock being joined at their swinging ends which terminate in outwardly bent portions integrally connected to cross bars 7 which constitute keepers. Corresponding cross pieces 4 of the other wall member 1 are spaced somewhat more closely as shown in Fig. 1 and adjacent pairs of these cross members terminate in loops 8 which open outwardly and rearwardly, the outer and rearward portions of the loops being integrally connected to cross bars 9 constituting pivots, the pivots being in a plane rearwardly of the plane of the keepers when the walls are in closed position as viewed in Fig. 1.

The latch of my invention comprises a plurality of pairs of hook elements 10 having eyes 11 engaging the pivots 9, the hooks 12 of these hook elements are engageable over the keepers 7 with a camming draw action. The hook elements are extended into arms 13 joining the bills of the

hook with a reversed curve 14 which provides a rounded or curved surface readily slidable over the keepers. The arms of these latch hook elements are connected by longitudinal bars 15. In the embodiment illustrated the outer hook elements of the adjacent central pair have their arms extended beyond the longitudinal bars 15, these arms being connected by the cross pieces 16 which constitute a hand piece for the latch. 10 With the loops 8 projecting outwardly and then for a substantial distance rearwardly, to resiliently support the latch pivots 9 and with the inner portions of the loop 8 having a positive retaining engagement with the keepers 7, as shown in Fig. 3, the hook elements 10, latch pivots 9 and keepers 7 all coact to provide springable camming locking engagement so that the wall members are not only effectively drawn or clamped on the mold contents, but it is practically impossible for the latching means to become accidentally disengaged. It is to be understood that the mold commonly receives the contents under compression and it is desirable to have means for securing the mold parts which 15 can be readily closed under such conditions and at the same time open quite easily. The handle portion 16 is preferably outwardly offset somewhat as shown in Fig. 2 for convenience in grasping. A hanger 17 is provided at one end of the mold. This however is old in the art.

I have illustrated and described my improvements in a very satisfactory embodiment thereof. I have not attempted to illustrate or describe other embodiments which I contemplate as it is believed that this disclosure will enable those skilled in the art to embody or adapt the same as may be desired.

Having thus described my invention, what I claim as new and desire to secure by Letters Patent is:

1. In a meat mold, the combination of a pair of pivotally connected wall members and closure means for said wall members, said closure means including cross pieces arranged in pairs and disposed crosswise each wall member, the cross pieces of the pairs on one wall member having their outer swinging ends integrally connected to cross bars outwardly offset from said wall and constituting keepers, the cross pieces of the pairs 45 on the other wall member terminating at their outer swinging ends in loops extending outwardly and then for a substantial distance rearwardly, pairs of said loops having their outwardly and rearwardly extending portions integrally connected to cross bars constituting latch pivots

disposed rearwardly of the keepers when the walls are in closed position, and a latch comprising a plurality of pairs of hook elements pivotally mounted on said pivots, said hook elements having arm portions extending beyond their hooks and merging therein with reversed curves disposed to provide keeper receiving recesses facing said latch pivots, a bar connecting the arm portions of said hook elements, certain of said hook element arms being extended beyond said bar and joined by a cross piece constituting a hand piece, said hook elements being swingably engageable over said keepers and conformed to engage them with a camming draw action, said latch pivots, keepers and hook elements coacting to provide springable camming locking engagement, the inner portions of said loops having positive retaining engagement with said keepers, when the hook elements are springably engaged over said keepers for locking engagement therewith.

2. In a meat mold, the combination of a pair of pivotally connected wall members and closure means for said wall members, said closure means including cross pieces arranged in pairs and disposed crosswise each wall member, the cross pieces of the pairs on one wall member having their outer swinging ends integrally connected to cross bars outwardly offset from said wall and constituting keepers, the cross pieces of the pairs on the other wall member terminating at their outer swinging ends in loops extending outwardly and then for a substantial distance rearwardly, pairs of said loops having their outwardly and rearwardly extending portions integrally connected to cross bars constituting latch pivots disposed rearwardly of the keepers when the walls are in closed position, and a latch comprising hook elements pivotally mounted on said pivots, said hook elements having arm portions extending beyond their hooks and merging therein with reversed curves disposed to provide keeper receiving recesses facing said latch pivots, a bar connecting the arm portions of said hook elements, said hook elements being swingably engageable over said keepers and conformed to engage them with a camming draw action, said latch pivots, keepers and hook elements coacting to provide springable camming locking engagement, the inner portions of said loops having positive retaining engagement with said keepers, when the hook elements are springably engaged over said keepers for locking engagement therewith.

3. In a meat mold, the combination of a pair of pivotally connected wall members and closure means for said wall members, said closure means including cross pieces arranged in pairs and disposed crosswise each wall member, the cross pieces of the pairs on one wall member having their outer swinging ends integrally connected to cross bars outwardly offset from said wall and constituting keepers, the cross pieces of the pairs on the other wall member terminating at their outer swinging ends in loops extending outwardly and then for a substantial distance rearwardly, pairs of said loops having their outwardly and rearwardly extending portions integrally connected to cross bars constituting latch pivots disposed rearwardly of the keepers when the walls are in closed position, and a latch comprising a plurality of pairs of hook elements pivotally mounted on said pivots, said hook elements having keeper receiving recesses facing said latch pivots, said hook elements having arm portions

extending beyond their hooks, a bar connecting the arm portions of said hook elements, certain of said hook element arms being extended beyond said bar and joined by a cross piece constituting a hand piece, said hook elements having camming engagement with said keepers, the inner portions of said loops having positive retaining engagement with said keepers when the hook elements are springably engaged over said keepers for locking engagement therewith.

4. In a meat mold, the combination of a pair of pivotally connected wall members and closure means for said wall members, said closure means including cross pieces arranged in pairs and disposed crosswise each wall member, the cross pieces of the pairs on one wall member having their outer swinging ends integrally connected to cross bars outwardly offset from said wall and constituting keepers, the cross pieces of the pairs on the other wall member terminating at their outer swinging ends in loops extending outwardly and then for a substantial distance rearwardly, pairs of said loops having their outwardly and rearwardly extending portions integrally connected to cross bars constituting latch pivots disposed rearwardly of the keepers when the walls are in closed position, and a latch comprising connected hook elements pivotally mounted on said pivots, said hook elements having keeper receiving recesses facing said latch pivots, said hook elements having arm portions extending beyond their hooks, said hook elements having camming engagement with said keepers, the inner portions of said loops having positive retaining engagement with said keepers when the hook elements are springably engaged over said keepers for locking engagement therewith.

5. In a meat mold, the combination of pivotally connected wall members, one wall member having keepers outwardly offset and spaced from said wall member, and the other wall member having loops extending outwardly and then for a substantial distance rearwardly, pairs of said loops having their outwardly and rearwardly extending portions connected by cross bars constituting latch pivots disposed rearwardly of the keepers when the walls are in closed position, and a latch comprising a plurality of pairs of hook elements pivotally mounted on said pivots, said hook elements having arm portions extending beyond their hooks and merging therein with reversed curves disposed to provide keeper receiving recesses facing said latch pivots, a bar connecting the arm portions of said hook elements, certain of said hook element arms being extended beyond said bar and joined by a cross piece constituting a hand piece, said hook elements being swingably engageable over said keepers and conformed to engage them with a camming draw action, said latch pivots, keepers and hook elements coacting to provide springable camming locking engagement, the inner portions of said loops having positive retaining engagement with said keepers, when the hook elements are springably engaged over said keepers for locking engagement therewith.

6. In a meat mold, the combination of pivotally connected wall members, one wall member having keepers outwardly offset and spaced from said wall member, and the other wall member having loops with outwardly and rearwardly projecting portions, latch pivots supported by the outer rearward portions of said loops, said latch pivots being disposed in spaced relation to the keepers when the walls are in closed position, and

a latch comprising connected hook elements pivotally mounted on said pivots, said hook elements having arm portions extending beyond their hooks and merging therein with reversed curves disposed to provide keeper receiving recesses facing said latch pivots, a bar connecting the arm portions of said hook elements, said hook elements being swingably engageable over said keepers and conformed to engage them with a

camming draw action, said latch pivots, keepers and hook elements coacting to provide springable camming locking engagement, the inner portions of said loops having positive retaining engagement with said keepers, when the hook elements are springably engaged over said keepers for locking engagement therewith.

DON L. TICHENOR.
